UNITED STATES PATENT OFFICE.

GEORGE K. GARVIN AND EDWARD J. McCLELLAN, OF NEW YORK, N. Y., ASSIGNEES TO
THE GARVIN MACHINE COMPANY, A CORPORATION OF NEW YORK.

HOLE-GRINDING MACHINE.

1,026,389.

Specification of Letters Patent.

Patented May 14, 1912.

Application filed August 11, 1911. Serial No. 843,487.

To all whom it may concern:

Be it known that we, GEORGE K. GARVIN and EDWARD J. McCLELLAN, citizens of the United States, residing at New York city, 5 in the county of New York and State of New York, have invented a new and useful Improvement in Hole-Grinding Machines, of which the following is a specification.

10 This invention relates to machines for grinding or finishing surfaces, and particularly interior surfaces such as the axial holes of hardened gears, ball races and the like.

15 Still more particularly the invention relates to a machine in which a grinding wheel or element rotates at a high speed, and which is moved longitudinally into and out of a hole to be ground in such a way 20 that when fully withdrawn from the hole the rotation of the work will be stopped and an opportunity given the workman to caliper the hole.

The invention has for one of its objects a 25 machine which is sensitive, *i. e.* which is operated by hand manipulation and in which the "feel" of the cut is constantly present in the control by the operator; (in practice an expert operator proceeds as 30 much by the "feel" in a sensitive machine as by sight.)

Another object of the invention is to provide for a very strong, compact and simple construction which is easily operated and 35 which is capable of performing a wide range of work or service.

The invention relates to an improved machine for grinding holes or surfaces in its various aspects.

40 The invention consists in the features of construction, combination, location and arrangement, as hereinafter set forth.

In the drawings, Figure 1, is a side elevation partly broken away of a grinding machine embodying the principles of this 45 invention; Fig. 2, is a top view of the same; Fig. 3, is an end view partly in section, and Fig. 4 is a detail view showing a support for the grinding wheel.

50 Constructions embodying the invention will include a spindle carrying a chuck which is adapted to be rotated, and also a spindle carrying a grinding wheel or cutter which rotates at high velocity, preferably

in a direction contrary to the direction of 55 rotation of the chuck spindle. The invention will further include means by which the grinding wheel and spindle may be given a movement so as to cause the grinding wheel to feed across the surface of the 60 work which is being ground.

In the drawings which illustrate the best practical constructions embodying the invention, 1 denotes a chuck-spindle, 2 a 65 chuck, 3 a grinding spindle and 4 a grinding wheel mounted on the grinding spindle.

5 denotes a carriage in which the grinding spindle is journaled, said carriage having a longitudinal movement in the frame 70 of the machine such frame being denoted 6 in the drawing.

8 denotes the head-stock or journal support for the chuck spindle. In accordance with the best constructions embodying the invention, the head-stock will be adjustable 75 to swivel in different directions in a horizontal plane, and will be further provided with a feed by which it may be given different lateral positions on the bed or frame 80 of the machine. As illustrated the head-stock has a circular base 9 with arc shaped slots 10.

11 denotes bolts or screws passed through the arcuate slots 10 and into the table or transversely movable frame 12. This table 85 or frame 12 has narrow ways 13 guided in corresponding ways 14 of the bed.

15 denotes a screw feed with a micrometer adjustment 16, the screw feed acting to position the table 12 and thereby the chuck 90 spindle in any lateral position.

Means may be provided for driving the chuck spindle and also the grinding spindle, and in the best constructions embodying the invention will include a drum 17 in a shaft 95 18 journaled in bearings 19 within the frame 6 and below the carriage 5. 20 denotes a shaft which as later described, may constitute a driving shaft. The latter shaft is located at the bottom of the frame 6. I 100 provide pulleys 24 and 25 on the respective shafts 18 and 20, connected by a belt 26 and providing for a high speed ratio between said drum and said shaft 20.

29 denotes a clutch of any suitable or desired character, and 30 denotes a sleeve constituting the driven member of the clutch and separate from the shaft 20 which con-

stitutes the driving shaft of the clutch. The sleeve 30 carries a pulley 31 belted by a belt 32 to a pulley 33 of the chuck spindle 1 through a reducing speed ratio. Means 5 are provided for engaging and disengaging the elements of the clutch 29 so as to put this clutch into and out of its driving relation. The means employed for this purpose may vary somewhat in practice, but 10 in accordance with the best practical embodiments of the invention, will be controlled from the carriage 5, and in such a way as to release said clutch only at or near the limit of the rearward movement of said 15 carriage.

Referring to the drawings, 35 denotes a segment-gear meshing with a rack 36 on the under side of the carriage 5. This segment-gear is fixed to a shaft 38 extending 20 transversely of the machine and having a crank or handle 40 by which the shaft and thereby the segment-gear are oscillated and the carriage 5 moved longitudinally of the bed. The carriage 5 has a long guide portion 41 in order to obtain an arcuate guide and for certain other purposes which will 25 later appear, and it is ordinarily made as light as possible, as of aluminum, and depressed or cut away at 42 in order to make it 30 as light and sensitive as possible. The depression 42 also gives a clearance for the swing of the chuck 2. 43 denotes a stop on the carriage which limits the forward movement thereof and which is adjustable. 35 These details of the carriage may of course vary somewhat in practice without departing from the spirit and scope of the invention.

45 denotes a pin forming in effect a crank-pin of the gear-segment and having depending therefrom a link or pitman 50 which is in turn connected to a bell-crank 51 with a fork 52 received in the groove or collar 53, said collar constituting a member for releasing the clutch 29 and being normally pressed in a direction to tighten said clutch by a spring 55 on the shaft 20. 56 denotes a fixed collar on said shaft to take the thrust of said spring 55.

50 59 denotes a slot in the link or pitman 50, the length of which is adjusted by the screw 60, and accordingly the pin 61 of the bell-crank 51 has a play in its relation to the pitman 50 determined by the length of this 55 slot. The effect is to cause an engagement of the bell-crank and the release of the clutch when the link 50 has been pulled upward a distance corresponding to the greatest retraction of the carriages. For any

60 position of ordinary service of the carriage the clutch 29 is not disengaged. It will be noted that the clutch is released by a toggle-joint action which makes the release easier. At the position of extreme retraction of the 65 carriage 5 the disengagement or release of

the clutch 29 will stop the rotation of the chuck spindle 1 and permit the work to be calipered.

Reference has been made to the fact that the movement of the carriage is made light and sensitive, and it is partly for this purpose that the carriage is made without adjustments such as lateral feeds, the grinding spindle 3 rotating in fixed bearing of the carriage. This gives rigidity combined with lightness, and minimizes vibration. Ball bearings, as "Hessbright" or other type, are used for the grinding spindle.

In accordance with the best constructions embodying the principles of the invention, a means for guiding the carriage in its movement will be employed which permits of ready adjustment, and which is not liable to wear or abrasion from emery dust or other abradent which may work into the interstices of the bed. The means will also be conducive to the sensitiveness and freedom of movement of the carriage to which I have referred. 62 indicates race-ways fixed horizontally at opposite sides of the carriage guide portion 41, and 63 indicates stationary race-ways on the bed co-operating with the race-ways on the carriage to provide prismatic grooves 64 in which the groups of balls 65 are received. The balls 95 will be constrained to remain in groups distributed at intervals along the respective race-ways, and for this purpose I provide pins 66 which project through the race-ways at intervals, such intervals corresponding to a distance at least half the maximum travel of the carriage plus the distance or length occupied by one group of balls. In this way the different groups of balls are kept distributed along a length of the carriage, so that the latter is adequately supported at all points of its length. At the same time it is freely guided with an almost frictionless movement and the nature of the ball and race-way relation in such that there is no appreciable wear from any emery dust which may find its way into the race-ways. One of the raceways 62 is adjustable in the bed of the machine, being free to move horizontally in its contained slot or groove and held at different positions of adjustment by the screws 70. By adjusting these screws any looseness may be taken out in both raceways simultaneously.

73 denotes strips of felt located over the race-ways 62, 63, and held down by metallic strips or weights. The purpose and effect is to preclude the entrance of emery into the race-ways.

In the use of the machine power is applied to the shaft 20 by a pulley 78; or to the shaft 18 by a motor (not shown) within the frame 6. The rotation of the drum is communicated to the grinding spindle or spindles by a belt or belts 79 at a multiplying speed 130

ratio, and on account of the length of the drum 17 this driving ratio is preserved for any position of the carriage, the belt traveling along the drum to new positions by a 5 familiar principle. The emery or grinding wheel or cutter 4 is carried on the grinding spindle, and I provide means by which a very small wheel or a very large wheel may be adequately supported. 80 denotes a pin 10 screwed into the end of the grinding spindle and adapted to constitute a hub or axis on which a small grinding wheel may be received. It will be evident that such a small wheel is properly centered and may 15 have an outside diameter scarcely greater than the outside diameter of the grinding spindle. This pin though adequate to hold a small grinding wheel is too small to properly support a large wheel. 20 85 denotes a bushing preferably with a coned central hole adapted to be slipped over a correspondingly tapered end of the grinding spindle. This bushing has a screw collar 87 and is adapted to receive a large 25 grinding wheel 88. The screw pin 80 in this case constitutes a means for holding the bushing on the spindle, a couple of washers or similar cap 90 being interposed if desired. Means are provided by which the rotation 30 of the chuck spindle is arrested promptly, although not so abruptly as to throw off any of the belts. It will be observed that the fork 52 of the bell crank 51, is engaged in a collar forming part of the clutch 29. As 35 shown the clutch 29 comprises a common type of which the outer casing rotates in one piece or unit and is loose on the shaft 20. The inner member 92 is fixed to the shaft. The movement of the collar 53 shifts the en- 40 tire clutch casing 29 to the right so as to loosen the clutch at the engaging faces 92, 93. At the same time the entire force of the spring 55 is brought into action to force the collar against the fork 52, and this produces 45 a friction or braking action which promptly arrests the rotation of the clutch 29. The chuck spindle 1 is therefore stopped promptly. During the normal running of the machine however, the force of the spring 50 55 is taken up between the face 93 and the collar 56 so that there is no force against any fixed bearing to interfere with the rotation of this shaft or produce heating. It will be understood that the chuck 2 may be 55 of any desired character but in order to co- operate with the other features of the invention the chuck 2 will be and is shown as an automatic chuck such as described in Patent No. 927,424, filed July 6, 1909, or our 60 copending application Serial No. 643,486, filed of even date herewith. In other words there will be a draw tube or rod within the spindle 1 and operated as described in the patents just referred to. The result is to 65 move the jaws into and out of clamping re-

lation on the work practically simultaneously with the stoppage of the rotation, and the jaws will furthermore always clamp the work in an exact relation to a given center or axis thereof.

70

What we claim is:—

1. In a machine of the class described, a chuck spindle, a grinding spindle, a transversely adjustable head-stock for said chuck spindle, a longitudinally movable carriage 75 for said grinding spindle, and means for stopping the rotation of the chuck spindle when said carriage is moved beyond a predetermined range.

2. In a machine of the class described, a 80 chuck spindle, a grinding spindle, a swiveled and transversely adjustable head stock for said chuck spindle, a longitudinally movable carriage for said grinding spindle, and means for stopping the rotation of said 85 chuck spindle when the said carriage is moved beyond a predetermined range.

3. In a machine of the class described, a chuck spindle, a grinding spindle, an adjustable head-stock for said chuck spindle, a 90 constantly rotating drum beneath said grinding spindle and belted thereto, said drum having a peripheral length equal to the travel of the carriage and a longitudinally movable carriage having bearings for 95 said grinding spindle.

4. In a machine of the class described, a chuck spindle, a grinding spindle, a carriage for said grinding spindle, a hand-lever connected to reciprocate said carriage longitudinally, and means operated by a movement of the said hand-lever beyond a predetermined range for stopping the rotation of said chuck spindle.

5. In a machine of the class described, a 105 chuck spindle, driving connections therefor including a clutch, a grinding spindle, a hand-lever for moving said grinding spindle longitudinally, and means including a slotted link connection for throwing out said clutch when said hand-lever is moved beyond a predetermined range.

6. In a machine of the class described, a chuck spindle, a grinding spindle, driving connections for said chuck spindle including 115 a clutch, a carriage for said grinding spindle having a rack on its under side, a hand-lever having a segment gear meshing with said rack, a link, and means connected to said link for throwing out said clutch 120 when the carriage moves beyond a predetermined range.

7. In a machine of the class described, a chuck spindle, a grinding spindle, driving connections for said chuck spindle including 125 a clutch, a carriage for said grinding spindle having a rack on its under side, a segment meshing with said rack, a link connected with said segment, a pin in said segment for said link, said link being located to 130

be on a dead center when at the end of its travel, whereby it is locked and held in this position, and means connected to said link for throwing out said clutch when the carriage moves beyond the predetermined range.

In testimony whereof, we have signed our names to this specification in the presence

of two subscribing witnesses, this 8th day of August, 1911.

GEO. K. GARVIN.
EDWARD J. McCLELLAN.
